UNITED STATES PATENT OFFICE

137,386

DESIGN FOR A MANIFOLD UNIT FOR RUBBER BOATS OR THE LIKE

William B. Kochner, St. Louis, Mo., and Lawrence T. Ward, East Orange, N. J., assignors to Knapp-Monarch Company, St. Louis, Mo., a corporation of Missouri.

Application July 14, 1943, Serial No. 110,670

Term of patent 14 years

To all whom it may concern:

Be it known that we, William B. Kochner and Lawrence T. Ward, citizens of the United States and residents of the city of St. Louis and State of Missouri, and of East Orange, in the county of Essex and State of New Jersey, respectively, have invented a new, original, and ornamental Design for a Manifold Unit for Rubber Boats or the like, of which the following is a specification, reference being had to the accompanying drawing forming a part thereof.

Figure 1 is a front elevational view of a mani-

fold unit for rubber boats or the like, embodying our new design.

Figure 2 is a side elevational view thereof; and

Figure 3 is a bottom plan view of Figure 1.

We claim:

The ornamental design for a manifold unit for rubber boats or the like, substantially as shown.

WILLIAM B. KOCHNER.
LAWRENCE T. WARD.
